UNITED STATES PATENT OFFICE.

CHARLES ROBINSON, OF TORONTO, ONTARIO, CANADA.

BUTTON AND STUD.

SPECIFICATION forming part of Letters Patent No. 241,722, dated May 17, 1881.

Application filed May 31, 1880. (Model.)

To all whom it may concern:

Be it known that I, CHARLES ROBINSON, of the city of Toronto, in the county of York, in the Province of Ontario, Canada, jeweler, have 5 invented certain new and useful Improvements in Shirt Studs and Buttons, of which the following is a specification.

This invention relates more particularly to an improved fastening for shirt and other studs 10 and buttons; and it consists in the combination, with a fixed prong, which extends first downwardly and then outwardly from the center of the bottom of the stud, of a similarly-shaped prong, which is movable around the 15 other prong for the purpose of fastening the stud to and detaching it from the shirt or other garment.

Referring to the accompanying drawings, 20 Figures 1 and 2 are perspective views of a stud embodying my improvements. Fig. 3 is a section, and Figs. 4 and 5 bottom plans of the same.

A is the stud, to the under side of which is 25 attached a fixed prong, B. This prong extends downwardly and then outwardly from the center of the stud, and on it is mounted the movable prong B', of substantially the same shape.

The prong B' is provided with a socket or 30 sleeve, b, which is fitted on the upright portion of the stationary prong and retained in position by a shoulder, b'.

Both prongs are of substantially the same 35 shape, and when placed in the position shown in Figs. 1, 3, and 4 form a retaining cross-bar, which effectually holds the stud in place. In this position the movable prong is held, by 40 means of the spring-arm B² and the cam-projection C, from displacement, while to prevent the prong being turned too far, a stop-block, D, 45 is provided, against which the arm B² bears.

Figs. 2 and 5 show the position of the prongs when fitting the stud into and detaching it from place. Here the prongs are brought close 45 together, forming but one bar, which can readily be passed into and out of a small opening in the shirt or other garment; and, if desired, the ends of the prongs can be pointed and be made to effect their own entrance by pressure.

50 The fixed prong B and the movable prong B', provided with the spring-arm B², made in

one piece therewith, are each made of wire. The fixed wire prong B is soldered or otherwise secured to the center of the stud, and is inserted while straight in the sleeve b, secured to the upright portion of the movable wire prong B', and after the insertion of the fixed wire prongs B into the sleeve the upper end of the former is bent at right angles to its vertical position over the upper end of the sleeve. 55 The function of the shoulder b' is twofold—viz., it retains the sleeve b on the upright portion of the fixed wire B and limits the revolution of the movable wire prong B' in one direction by acting as a stop, the movement of 60 the movable wire prong in the opposite direction being limited by the cam-projection C and stop D.

I am aware that Letters Patent for a button-fastening have been granted L. Goodwin, 70 dated June 29, 1858, No. 20,707, and I therefore lay no claim to such invention, which differs from my construction in several important particulars, among which the following may be enumerated, viz: The prongs of Goodwin are not formed of wire; nor are the movable prong and its revolving arm made in one piece, nor provided with a sleeve secured to the movable prong and adapted to rotate on the fixed prong; nor is a shoulder employed 75 by Goodwin retaining the sleeve in place, and also acting as a stop to limit the movement in one direction of the movable prong.

My construction is different, simpler, and cheaper than the invention disclaimed, and the 80 parts more readily put together.

I claim as new and desire to secure by Letters Patent—

The combination, with the stud-head A, having the projections C D on its lower face, of 90 the fixed angular wire prong B, provided with the shoulder and stop b', and movable angular wire prong B', provided with the wire spring-arms B², formed therewith, and sleeve b, secured to the movable arm and fitting around 95 the upright part of the stationary wire prong, substantially as described, and for the purpose set forth.

C. ROBINSON.
